SURFACE ORNAMENTATION OF WALLS, &c.

No. 16,241.

Patented Sept. 8, 1885.

Fig. 2.

Fig. 1.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,241, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and 5 original Design for Surface Ornamentation of Walls, &c., of which the following is a specification, reference being had to the accompanying photograph, forming part hereof.

Figure 1 shows my new design. Fig. 2 is 10 a longitudinal section of the same.

My design includes both the configuration or pattern hereinafter described, and also on the surface of the curved portions of said pattern an appearance of the grain different from 15 that which is seen on the flat parts of said pattern.

My new design consists of a series of rounded elevations, A, placed in juxtaposition, and extending across the surface. Upon each elevation A is shown a narrow flat elevated band, 20 B. The surface of the rounded or curved por-

tions presents peculiar configurations of the grain, which configurations are different from those which appear on the flat bands B. My design is therefore ornamental in the configuration of its elevations and depressions, and also in the variegated character of the grain. 25

I claim—

The design for a surface ornamentation of walls, &c., herein shown and described, consisting in a series of curved or rounded elevations, A, in juxtaposition and extending transversely across the surface, and on each elevation a narrower flat-surfaced elevation, B, the rounded parts of said pattern showing a different marking of grain from that appearing on the flat parts of said pattern. 30 35

FREDERICK MANKEY.
